UNITED STATES PATENT OFFICE

JEFFERSON DAVIS SCRIVNER AND ROY OAKLEY STARBUCK, OF SAN BENITO,
TEXAS

SUN-BATH CABINET

Application filed July 22, 1929. Serial No. 380,094.

The invention relates to a new and improved enclosure or cabinet for use by sun bathers to obtain privacy regardless of the locality in which sun bathing is to be done.

5 One object of the invention is to provide a novel construction which may readily be carried to the point of use in folded condition and may be quickly and easily erected for use.

10 A further object is to provide a unique frame structure embodying novel and efficient bracing and anchoring means for use where guy wires or ropes cannot be conveniently employed.

15 Another aim is to provide novel means for connecting a canopy with the cabinet to convert it into a tent when desired.

With the foregoing in view, the invention resides in the novel subject matter hereinafter described and claimed, description being accomplished by reference to the accompanying drawings.

Fig. 1 is a perspective view of a bath cabinet constructed in accordance with our invention showing the entrance partly open.

25 Fig. 2 is a perspective view of the frame structure.

Fig. 3 is an enlarged detail perspective view illustrating the manner of fastening the brace bars of Figs. 1 and 2 to the corner posts.

30 Fig. 4 is an enlarged detail perspective view illustrating the manner of connecting the lower ends of the brace bars and anchoring them to the ground.

Fig. 5 is a perspective view of the cabinet shown in Fig. 1 but illustrating the canopy attached thereto and supported by a center pole.

Fig. 6 is a perspective view similar to Fig. 1 but illustrating guy ropes or wires instead of brace bars.

40 Fig. 7 is an enlarged detail perspective view illustrating the manner in which the side wall supporting rope or wire may be connected with eyes on the upper ends of the corner posts, in the construction shown in Fig. 6.

45 The form of construction illustrated in Figs. 1 to 5 will first be described. In these views, a novel frame structure is employed, embodying corner posts 9 having either closed 50 or open eyes 10 at their upper ends to receive

a side wall supporting line 11 which may be of rope or wire. After passage of the line through the eyes 10 or merely hooking it into these eyes if the latter be of open form, the line is drawn taut and its ends secured together by any desired means such as the clamp 12. Other clamps 13 are provided for securing the lower ends of the posts 9 to stakes 14 driven into the ground. Should the stakes become loosened, the clamps 13 may be loosened and said stakes driven further downward, whereupon the clamps will again be tightened.

55 Inclined braces 15 are provided for the corner posts 9, there being two braces for each post, as shown. The upper ends of these braces are provided with upstanding lugs 16 detachably bolted at 17 to the posts 9. The lower ends of the braces 15 are provided with flat horizontal feet 18 to rest upon the ground, 60 said feet projecting inwardly toward each other and being provided with upstanding studs 19. Flat horizontal bars 20 lie upon the feet 18 and are provided at their ends with openings 21 removably receiving the studs 19, and between their ends, these bars are formed 65 with additional openings 22 through which headed spikes 23 are driven to anchor said bars to the ground.

70 By providing the novel frame structure shown and described, it may readily be assembled or disassembled as desired, compactly arranged for carriage from one point to another, and whenever desired may be stored in this compact condition. Regardless of the 75 sectional construction of the frame, it will be of rigid nature when properly assembled, and it will be seen that the inward pull of the line 11 will be effectively resisted by the braces 15 and associated parts.

80 A flexible side wall 24 surrounds the frame structure above described and is provided with supporting hooks 25 detachably engaged with the line 11, the ends of said wall being 85 overlapped to form an entrance. When this wall is applied and the entrance closed, the sun bather is afforded the desired privacy.

85 In some instances, it is desirable to convert the cabinet into a tent. When this is to be 90 done, a canopy 26 may be used as shown in 95

Fig. 5, said canopy being provided with hooks 27 near its edge to engage the line 11 and being supported at its center by a pole 28.

Fig. 6 discloses a construction in which guy ropes or the like 29 are used instead of the braces 15. The line 11^a in this form of construction is preferably secured to the eyes 10^a, for instance, as shown in Fig. 7, so that it will serve as spacing means for the posts 9^a. The ends of the line are preferably permanently secured together as at 12^a. This line supports a side wall 24^a in the same manner as line 11 supports wall 24 and if desired, the canopy 26 may be used with this construction also.

15 On account of the results obtainable from the details disclosed, they are preferably followed. However, within the scope of the invention as claimed, variations may be made.

We claim:—

20 1. A portable sun bath cabinet comprising a plurality of corner posts for engagement with the ground at their lower ends, eyes carried by the upper ends of said posts, a continuous flexible line engaged with said eyes 25 and having taut reaches extending between all of said posts, brace means for the posts resisting the inward pull of said line, and a flexible side wall suspended from said line.

2. A structure as specified in claim 1; together with a canopy having hooks to engage said line, and a pole for supporting the center of said canopy.

3. In a portable structure, a plurality of corner posts, a line connected with the upper ends thereof, means for anchoring the lower ends of said posts to the ground, inclined braces detachably connected to said corner posts and having feet to rest on the ground, elongated bars whose ends lie upon said feet, connecting means between said bars and feet, and means for anchoring said bars to the ground.

4. In a portable structure, a plurality of corner posts having eyes at their upper ends, a line engaged with said eyes, means for anchoring the lower ends of said posts to the ground, inclined braces having upstanding lugs at their upper ends detachably bolted to said posts, the lower ends of said braces being provided with feet to rest upon the ground, said feet having upstanding studs, horizontal bars whose ends rest on said feet and are formed with openings removably receiving said studs, said horizontal bars having additional openings between their ends, and headed spikes for passage through these openings to anchor said horizontal bars to the ground.

5. In a portable structure, two corner posts, two downwardly converging brace bars detachably connected with said posts respectively, the lower ends of said brace bars being provided with feet to rest upon the ground, a horizontal bar whose ends lie upon said feet, connecting means between said ends of said horizontal bar and said feet, and means for

anchoring said horizontal bar to the ground.

6. In a portable structure, two corner posts, two downwardly converging brace bars respectively, the lower ends of said brace bars being provided with feet to rest upon the ground, said feet each having an upstanding stud, a horizontal bar whose ends lie upon said feet and are formed with openings removably receiving said studs, and means for anchoring said horizontal bar to the ground.

7. In a portable structure, two corner posts, two downwardly converging brace bars respectively, the lower ends of said brace bars being provided with feet to rest upon the ground, said feet each having an upstanding stud, a horizontal bar whose ends lie upon said feet and are formed with openings removably receiving said studs, said horizontal bar having an additional opening between its ends, and a headed spike for passage through this opening to anchor said horizontal bar to the ground.

In testimony whereof we have hereunto affixed our signatures.

JEFFERSON DAVIS SCRIVNER.
ROY OAKLEY STARBUCK.
